BAFFLED ROTARY KILN

Thorkild Avnsoe, Bellerose, and Ejnar Posselt,
Pelham, N. Y., assignors to International Cement Corporation, New York, N. Y., a corporation of Maine

Application March 9, 1934, Serial No. 714,742

13 Claims. (Cl. 263—22)

This invention relates to the construction of a rotary kiln and more particularly to the provision of baffles within the kiln. In the use of a rotary kiln for the burning of 5 Portland cement and similar products, very low thermal efficiency is obtained. The load entering the upper end of the kiln as raw mix lies in a solid mass on the lower portion of the inside of the kiln, forming a layer 12" to 18" deep and 10 occupying only a very small part of the cross section of the kiln. This condition is very unfavorable to proper and efficient transfer of the heat required to calcine and clinker the material and a large amount of heat is retained in the gases 15 leaving the kiln. Furthermore the CO₂ carried along with the gases forms a blanket of CO₂ saturated air over the mix during calcination and retards the dissociation of the CaCO₃.

Various attempts have been made to improve 20 these conditions but because of the high temperatures encountered it has been difficult or uneconomical to accomplish the desired improvement.

It is an object of the present invention to provide an improved construction whereby the exposed surface of raw material is increased; the CO₂ liberated during the calcining is agitated and removed from the surface of the raw material; the material being treated is cascaded directly through the hot gases; the length of the calcining zone and the radiating losses may be reduced; and the parts exposed to the heat may be maintained at a sufficiently low temperature to assure low maintenance cost. It is also an 35 object to provide improved means for supporting and cooling baffles within a rotary kiln. Another object is to provide an improved arrangement for supplying cooling air to the baffle. A further object is to provide an improved construction for 40 retaining members within the kiln whereby the expansion and contraction of the kiln will be accommodated. Other objects will become apparent.

In describing the invention reference will be 45 made to the drawings in which,

Figure 1 is a side elevation of the improved kiln and cooling unit with portions of the kiln and cooler broken away opposite the baffles.

Figure 2 is a fractional top plan view opposite 50 one set of baffles.

Figure 3 is a section taken on the line 3—3 of Figure 1.

Figure 4 is a fractional diagrammatic view illustrating the means for retaining one end of the 55 tubes in the shell of the kiln and Figure 5 is a

similar view of the means for retaining the other end of the tube.

Figure 6 is a diagrammatic section through the kiln illustrating the manner in which the baffles are installed. 5

Figure 7 is a fractional side elevation of the kiln with the blowers removed and with portions cut away to illustrate the baffle construction and tubes, and

Figure 8 is a section taken on the line 8—8 of 10 Figure 7 a portion being broken away to illustrate the tubes.

In the drawings the numeral 10 designates a rotary kiln and 11 a cooler. The kiln is heated by a burner at its lower end (not shown) or other 15 suitable means. The cooler is provided with means for supplying a current of air over the surface of the material therein (not shown). The kiln is rotated by the motor and gearing indicated at 12 and the cooler may be driven from 20 the kiln by a suitable gear or chain (not shown) or may be driven by a separate driving unit similar to that illustrated at 12.

The kiln is provided with the usual lining 13 of refractory material and with a plurality of 25 baffles 14 spaced apart and positioned intermediate the ends of the kiln, preferably in the calcining zone. The spaced baffles 15, extend at right angles to the baffles 14 and are alternately positioned in relation to them. The baffles are made 30 up of a plurality of pipes or tubes 16 extending through and supporting a series of blocks 17. These blocks 17 are elongated blocks of refractory material each having a plurality of holes for the pipes 16 and being shaped to fit into each 35 other and to form a continuous baffle. The pipes 16 are open to the air at their outer ends and at their inner ends are connected to a manifold communicating with an air blower. The pipes of the baffles 14 are connected to manifold 18 40 communicating with air blower 19 having an air intake 20 and the pipes of baffle 15 are connected with the manifold 21 communicating with the air blower 22 having an intake 23. The air blower 22 is preferably positioned diametrically opposite 45 the blower 19 in order that the weight may be balanced around the circumference of the kiln.

The cooler 11 is also provided with baffles 24 and 25 spaced apart and positioned at right angles to each other. These baffles are provided 50 with similar pipes, which pipes are open to the air at their outer ends and communicate at their inner ends with manifolds 26 and 27, both of which manifolds communicate with a single air blower 28 having an air inlet 29. If preferred 55

this arrangement may be used on the kiln or the arrangement shown on the kiln may be used on the cooler.

In operating the kiln the raw mix is charged 5 into the upper end of the inclined kiln 10 and as the kiln rotates the mix passes downwardly through the kiln toward the burning zone and the discharge end. As the material passes through the portion of the kiln having the baffles 10 14 and 15 therein it is agitated and tumbled by the baffles and new surfaces are exposed to the hot gases from the burner. The mixture then passes on into the final burning zone and the burned cement is discharged into the receiver 15 for the cooler 11. As the burned clinkers are fed through the cooler 11 they are agitated by the baffles 24 and 25 to give better contact with the cooling air introduced at the lower end of the cooler, which cooling air may be discharged 20 in preheated condition from the upper end of the cooler and used as a source of preheated air in the burners for the kiln or in some other manner.

Cooling air is forced through the pipes 16 by 25 the blowers which rotate with the kiln and may be operated by a motor supplied with current through a collector ring 39 or by other suitable means.

Because of the expansion and contraction of 30 the kiln upon heating and cooling, each pipe 16 is fixed to the shell of the kiln or cooler at only one end. This is accomplished by a collar 30 threaded to an end of the pipe 16, which collar 30 is fixed to the shell by the bolts 31 projecting 35 from the plate 32 which is riveted to the shell as illustrated at 33. The other end of each pipe 16 is retained by the tightly fitting collar 34 which is bolted to the plate 35 by means of the bolts 36, the plate 35 being riveted to the shell as illustrated at 37.

With this arrangement the expansion of the shell will cause the tightly fitting collars 34 to slip along the pipes 16 thus accommodating expansion and contraction of the shell.

45 The baffles may be installed as illustrated in Figure 6. A temporary scaffolding 38 may be inserted within the kiln and the blocks 17 may be laid out on the top of the scaffolding with their apertures registering with the oppositely positioned apertures in the shell. The pipes 16 may then be slipped through the apertures and the collars 30 may be bolted to the plate 32. The collars 34 may then be applied to the other ends of the pipes 16 and bolted to the plate 35.

55 It is obvious that many variations may be made in the above apparatus and it is not intended to limit the invention to the particular arrangement or details shown or described. For example, the arrangement or numbers of the baffles may be varied or they may be placed at different angles to each other or all in the same plane or, if desired, only one section may be used. Also the means for cooling the baffles may be different or the means for supplying the cooling gas or liquid 60 may be altered. The blowers and manifolds may be differently arranged and if desired the air or other cooling medium may be drawn through the pipes 16 by the blower or a pump instead of being forced through them or in some cases sufficient cooling may be accomplished by a natural 65 draft through the tubes, in which case the details of the invention may be utilized without using the blowers. The construction and means for supporting the baffles or the means for retaining 70 the pipes may also be altered to suit particular 75

conditions. If desired, the position of the baffles longitudinally of the kiln may be varied, although it is preferred to use the arrangement shown.

The terms and expressions used in describing 5 and claiming the invention have been used in their descriptive senses and not as terms of limitation and it is intended that all equivalents of the terms used be included within the scope of the appended claims.

10 What we claim is:

1. A rotary cement kiln having an inlet at one end for cement materials and an inlet at the other end for fuel, comprising a shell having a plurality of transverse longitudinally extending baffles 15 spaced from each other in the calcining zone of the kiln.

2. A rotary kiln comprising a shell having therein a plurality of transverse baffles extending longitudinally of the kiln and spaced from each 20 other longitudinally of said kiln and angularly positioned relative to each other.

3. A rotary kiln comprising a cylindrical shell having therein a plurality of longitudinally spaced diametrically positioned baffles angularly positioned relative to each other and extending longitudinally of the kiln.

4. A rotary kiln comprising a cylindrical shell having therein a plurality of longitudinally spaced diametrically positioned baffles at right angles to 30 each other and extending longitudinally of the kiln.

5. A rotary kiln comprising a shell and a transverse baffle within the calcining zone thereof having a series of tubes extending through it and the adjacent portion of the shell, and an air blower carried on said shell and adapted to force air through said tubes.

6. A rotary kiln comprising a shell, a plurality of baffles positioned in said shell with air conduits extending through them and the adjacent portions of the shell, and air blowers positioned at diametrically opposed positions on said shell and adapted to force air through said conduits.

7. A rotary kiln comprising a shell, a plurality of longitudinally spaced baffles positioned at angles to each other in said shell and having air conduits adapted to conduct cooling currents of air through said baffles, and a plurality of air blowers positioned at diametrically opposed positions on said shell, and adapted to force air through said conduits.

8. A rotary kiln comprising a shell having a plurality of shelves therein extending longitudinally of the kiln and spaced from each other, each said shelf having means for conducting a cooling medium through it.

9. In a rotary kiln, a shell, a plurality of refractory partitions extending longitudinally of the kiln and arranged to serve as baffles for material 60 moving circumferentially of the shell, said partitions being longitudinally spaced from each other with respect to the shell, and means to cool said partitions.

10. In a rotary kiln, a shell, a plurality of refractory partitions in the calcining zone of said shell extending longitudinally of the kiln and arranged to serve as baffles for material moving circumferentially of the shell, said partitions being longitudinally spaced and angularly disposed 70 to each other with respect to the shell, and means to cool said partitions.

11. A rotary cement kiln comprising a shell having therein a plurality of transverse baffles extending longitudinally of the kiln and spaced from 75

each other longitudinally of said kiln and angularly positioned relative to each other, said baffles being positioned in the calcining zone of the kiln.

12. A rotary kiln comprising a shell, a plurality of partitions extending longitudinally of the kiln and arranged to serve as baffles for material moving circumferentially of the shell, said partitions being longitudinally spaced from each other and comprising a plurality of hollow tubes encased in refractory material.

13. A rotary kiln comprising a shell, a plurality of partitions extending longitudinally of the kiln and arranged to serve as baffles for material moving circumferentially of the shell, said partitions extending diametrically across the shell, being 5 spaced longitudinally from each other, and comprising refractory material surrounding a plurality of pipes.
